UNITED STATES PATENT OFFICE.

EDWARD L. KELLAN, OF CHICAGO, ILLINOIS.

SLOW-CLOSING MIXING-FAUCET.

1,366,081.

Specification of Letters Patent. Patented Jan. 18, 1921.

Application filed April 1, 1916. Serial No. 88,229.

To all whom it may concern:

Be it known that I, EDWARD L. KELLAN, a citizen of the United States, and a resident of Chicago, in the county of Cook and State of Illinois, have invented certain new and useful Improvements in Slow-Closing Mixing-Faucets; and I do hereby declare that the following is a full, clear, and exact description thereof, reference being had to the accompanying drawings, and to the characters of reference marked thereon, which form a part of this specification.

This invention relates to a novel slow closing faucet for use in connection with lavatories or other places where it is desired to draw a certain quantity of water and insure that the faucet will not remain open and the water be allowed to run indefinitely after the original charge of water has been used.

The device embodying my invention is adapted more especially for use in hotel and like public wash rooms.

In places where water is paid for at meter rates the loss occasioned to the proprietor of such a place due to the fact that the patrons leave the faucets open is considerable, and for this reason, it is a general practice to equip such places with quick closing faucets to avoid waste.

It is the purpose of my invention to provide a faucet which will furnish a flow of water sufficiently long to fill a lavatory bowl without maintaining the hand pressure on the faucet or, if desired to wash the hands in running water, to furnish a supply sufficient for this purpose, in one operation of the faucet, and which will also close after a predetermined time to prevent wastage of water.

The invention consists in the combination and arrangement of the parts shown in the drawings and described in the specification and is pointed out in the appended claims.

45 In said drawings:—

Figure 1 is a side elevation of a faucet embodying my invention.

Fig. 2 is a top plan view thereof.

Fig. 3 is a vertical section on the line 3—3 50 of Fig. 1.

Fig. 4 is a horizontal section on the line 4—4 of Fig. 3.

Fig. 5 illustrates the details of the timing

piston which controls the closing movement of the valve.

55

Fig. 6 is a detail view of one of the shells on which one of the valve seats is formed and through which communication is had from one of the inlets of the valve to the common outlet, assuming a double valve. 60

As shown in the drawings 10 designates a valve casing which, in a double valve, is of oblong cross section as shown in Figs. 2 and 4. In the double form of valve the said casing is provided with two inlet members 11, 65 11, one adapted for connection with the hot water pipe and the other for connection with the cold water pipe, and a common outlet member 12 to which is connected the downturned discharge member 13. The said 70 casing is provided with a flange 15 which rests on the upper face of the lavatory bowl 16, or other part to which the fixture is adapted to be attached. The inlet members 11 extend through suitable openings in the 75 part 16 and are screw threaded at their lower ends to receive clamping nuts 17 between which latter and the part 16 may be interposed suitable washers 18.

As herein shown the elements of one 80 valve device are duplicates of the elements of the other valve device and in the following description but one of the valve devices is assumed, except where necessary reference is made to two like parts to explain the co- 85 operation of one side of the valve to the other.

Arranged within the casing 10 are two shells 20, each of which has a restricted lower end 21 which extends into the appropriate inlet pipe 11 and an upper enlarged portion 22 provided with a series of openings 23 which afford communication between the inlet pipe and the valve casing when the valve is open. Between the larger and 90 smaller portions of the shell 20 is formed a flat shoulder, and between said shoulder and the floor of the casing around the restricted portion 21 is interposed a yielding washer 25 to provide a water tight joint. 95

100

27, 27, designate cylinders which are screw threaded at their lower ends to engage into screw threaded apertures at the upper side of the valve casing for a purpose herein-after to be described. The bottoms of said 105 cylinders 27 bear upon the upper ends of

the shells 20 and the screw threaded connections of the shells with the casing serve to exert a clamping pressure on the washers 25 as will be evident.

5 30, 30, designate valves which coöperate with seats 31 formed on the lower ends of the smaller portions of the shells 20. Each of said valves is carried by the lower end of a stem 32 which extends upwardly into the 10 cylinder 27 and through a stuffing box formed in an extension 33 of the cylinder. The upper end of said stem is provided with a head 34, between which and the following member 35 of said stuffing box is interposed an expansively acting spiral spring 36 which surrounds said stem. The said spring 36 serves to normally hold the valve 30 against its seat. The spring is so proportionated to the throw of the valve stem that 20 it remains under restraint when the valve is closed so that thereby there is maintained a continuous spring pressure on the yieldable body 37 of the stuffing box to insure a liquid tight joint between the valve stem and the 25 surrounding parts.

The cylinders 27 constitute parts of a timing arrangement which operates to time the closing movements of the valves. They are filled with oil or other suitable fluid. Arranged within each cylinder is a piston 40, the elements of which are shown best in Figs. 3 and 5. Said piston is carried by the lower end of a reciprocating, hollow stem 41 which extends through the upper end of 35 the cylinder and through a stuffing box 42 carried thereby. As herein shown the upper end or wall of the cylinder comprises a screw threaded cap 43 between which and the end of the cylinder is clamped a packing 40 washer 44. The said cap has a central, up-standing, externally, screw-threaded nipple 45 over which fits the cap 46 of the stuffing box and between the outer end of the cap and the follower member of the stuffing box 45 is interposed a spring 47 by which to maintain a constant yielding pressure on the compressible member of the stuffing box. The stem 41 is provided at its upper end with a removable head or thumb piece 48, herein 50 shown as screw threaded to the stem.

The piston 40 comprises upper and lower disks 50, 51, respectively, between which is confined the usual cup leather 52 which latter has sliding engagement with the inner 55 wall of the cylinder 27, and said members 50, 51, are screw threaded to the reduced lower end of a fitting 41' which latter is here shown as screw threaded to the lower end of the stem 41.

60 Communication is afforded from the space in the cylinder below the piston to the space therein above the piston through a by-pass comprising an axial passage 55, which opens at the lower side of the piston and a 65 lateral passage 56 which opens above the

piston, said passages being formed in the fitting 41'.

The flow of liquid through said by-pass is controllable so as to thereby regulate the time of closing of the valve by a regulating 70 device which is made as follows:

58 designates a rod which extends through the hollow reciprocating stem 41. It is provided at its lower end with a reduced screw threaded portion 59, the terminal of which constitutes a valve to control the by-pass, composed of the passages 55, 56. Said screw threaded portion of the rod has screw threaded engagement with internal screw threads of the fitting 41' surrounding 80 the passage 55 whereby, when said rod is rotated on its axis, it is adjusted toward or from the lateral portion 56 of the by-pass so as to regulate the flow of liquid therethrough. Said rod is grooved at its upper 85 end to receive a screw driver or like implement by which it may be turned on its axis when the thumb piece 48 is removed to thereby adjust the by-pass valve device. In order to prevent the escape of liquid past the screw threaded end of the rod 58, the space surrounding the said reduced screw threaded portion of the rod within the lower end of the hollow stem 41 is filled with a suitable packing material 61, as shown in 90 Fig. 3. Said packing is confined between the shoulder on the rod 58 formed between the larger and smaller portions of the rod and the internal shoulder formed between the larger and smaller portions of the fitting 41'.

In the operation of the device, pressure on the thumb piece 48 depresses the piston 40 which in turn acts on the valve stem 32 to force the valve 30 away from its seat 31. 105 The water, under pressure, escapes past the valve into the valve casing 10 and outwardly through the outlet 13. In order to hasten the opening movement of the valve the dimension of the cup leather of the 110 piston 40 is such, relatively to the internal diameter of the cylinder 27, that when the piston is thus forced downwardly to open the valve 30, the liquid within the cylinder 27 is free to flow around the piston so that 115 as the valve is depressed the liquid is displaced from the lower to the upper side of the piston. When the valve is so depressed the spring 36 is placed under compression and power is stored therein to close the valve 120 when hand pressure is released. The closing movement of the valve under the action of the spring 36, however, is retarded by reason of the fact that the displacement of the liquid from the upper to the lower side of the piston, in the upward movement of said piston, is restricted by the by-pass comprising the passages 55, 56. By reason of the regulable action of the valve 59, with respect to the by-pass, the by-passing of the liquid 125

in the cylinder 27 may be so variably retarded as to variably control the closing movement of the valve. It will be evident, however, that the valve will, within the period predetermined by the regulation described, be fully closed by the spring 36 so as to thereby avoid wastage of water.

In order to prevent the entrance of particles carried in suspension by the liquid into the by-pass during the upward movement of the piston 40, I have provided a screen 63, shown in Figs. 3 and 5, which surrounds the upper end of the fitting 41' and is clamped in place by means of a bell shaped clamping member 64 that has screw threaded engagement with the lower end of the stem 41 and bears at its lower annular edge against a marginal flange 65 of the screen, best shown in Fig. 5. The said bell shaped member is provided with one or more openings 66 through which liquid may flow.

By reason of the fact that the by-passes of the two sides of the valve are independently regulable it will be noted that the timing elements of the two sides of the valve may be so adjusted relatively to each other that a larger volume of water may flow through one side of the valve than the other. It is thus practical therefore to adjust the faucet to supplies of hot and cold water differing in their relative temperatures so as to obtain as a result of the mixing of the hot and cold water a mixture of a desired temperature.

Attention is also called to the fact that the operating stems and the timing pistons are made, as unitary parts, separate from the valve and their stems. This construction not only simplifies the manufacture of the valve and reduces its cost but also enables said timing pistons to be removed from the timing chambers without disturbing the settings of the valves, thereby simplifying the cleansing of the valve and replacement and repairs of the parts associated with the timing mechanism and the replenishment of the liquid in the timing cylinder, all without shutting off the water which the valve controls.

By reason of the screw threaded connection of the timing shells or chambers 27 with the valve chamber 10, the valves 30 may be readily exposed for the purpose of repair or renewal by unscrewing the cylinders 27 from said casing and lifting said cylinders, together with the valves carried thereby away from the casing, the inlet openings in the floor of the casing being sufficiently large to permit the valves 30 to pass therethrough.

It will be understood that the structural details of the valve illustrated may be somewhat varied within the spirit and scope of the claims hereto appended and that the invention is not limited to said details except as to such claims wherein said details are

specifically pointed out, and as imposed by the prior art.

I claim—

1. A slow closing faucet comprising an integral casing provided with two inlets and inclosing a common mixing chamber, a common outlet through which the mixed liquids from the inlets are discharged, upstanding extensions in line with said inlets and integral with said casing, cylinders connected to said extensions, ported members on which inlet valve seats are formed, and confined between said cylinders and the integral casing, and pistons in said cylinders connected to said valves and forming with the cylinders timing means to control said valves.

2. A slow closing faucet comprising an integral casing provided with two upstanding extensions, two inlets, a single mixing chamber, and a common outlet, timing cylinders threaded into said extensions, and having reduced lower ends inclosed by said extensions and into which stems extend, the lower reduced ends of the cylinders within said extensions constituting parts of stuffing boxes, the stems extending through said stuffing boxes into said cylinders, and timing means within the cylinders connected to said stems and relatively operable in time to separately control the closing movements of the valve.

3. A slow closing faucet comprising an integral casing provided with two upstanding extensions, two inlets, with their controlling valves, a single mixing chamber, and a common outlet, timing cylinders threaded into said extensions, and having reduced lower ends inclosed by said extensions, stems extending through the said reduced parts of the cylinders, the lower ends of the cylinders within said extensions constituting parts of stuffing boxes through which the stems extend, and timing means within the cylinders connected to said stems and relatively operable to separately control the closing movements of the valves, there being ported members within said extensions coaxial with the inlets and cylinders that are confined between shoulders on the cylinders and casing and on which are formed seats to constitute parts of the inlet valve structure.

4. A slow closing faucet comprising a casing provided with two inlets and a common outlet, valves to control said inlets and provided with stems, timing cylinders into which said stems extend, pistons separate from said stems and reciprocable in said cylinders, hollow operating stems connected to said pistons and extending from said cylinders and acting through the pistons and stems to open the valves, operating springs for said valves and said pistons, said pistons being provided with by-

passes to by-pass liquid from one side to the other of the pistons, and screw threaded rods in said operating stems adapted to control the flow of liquid through said piston by-passes.

5. A slow closing faucet comprising a casing provided with two inlets and a common outlet, valves to control said inlets provided with upwardly extending valve stems, liquid containing, timing cylinders mounted on said casing in axial alinement with the valves and provided with openings upwardly through which the valve stems extend, stuffing boxes for said valve stems, heads at 15 the upper end of said stems, springs interposed between said stuffing boxes and said heads, pistons in the cylinders, separate from said valve stems, and adapted, upon depression, to act on the stems to unseat the 20 valves and to be restored by the restoring valve springs, there being by-passes provided to by-pass liquid from one side of the pistons to the other and manual operating means for said pistons.

25 6. A faucet comprising a casing having an inlet and an outlet, a shell within the casing having a reduced part which extends through the casing floor into the inlet and formed at its lower end to constitute a valve 30 seat, a cylinder axially alined with said shell and having a portion extending into and having screw threaded engagement with the casing, a valve to engage said seat and provided with a stem which extends into said 35 cylinder, a packing between a shoulder on

the shell and the floor of the casing, said screw threaded cylinder engaging the shell and acting therethrough to compress said packing, and an operating and timing device in said cylinder coöperating with the 40 valve stem to control said valve.

7. A faucet comprising a casing having an inlet and an outlet, a shell within the casing having a reduced part which extends through the casing floor into the inlet and 45 formed at its lower end to constitute a valve seat, a cylinder axially alined with said shell and having a portion extending into and having screw threaded engagement with the casing, a valve to engage said seat 50 and provided with a stem which extends into said cylinder, a packing between a shoulder on the shell and the floor of the casing, said screw threaded cylinder engaging the shell and acting therethrough to 55 compress said packing, and an operating and timing device in said cylinder coöperating with the valve stem to control said valve, the opening in said casing floor being of a diameter to permit said valve to be 60 passed freely therethrough.

In testimony, that I claim the foregoing as my invention I affix my signature in the presence of two witnesses, this 6th day of January A. D. 1916.

EDWARD L. KELLAN.
